Primary Examiner—Nanda Bondade

Assistant Examiner—Shanda C. Hill

(74) Attorney, Agent, or Firm—Sheridan Ross P.C.

(57) **CLAIM**

The ornamental design for a metallic microwavable container, as shown and described.

DESCRIPTION

FIG. 1 is a perspective view of a metallic microwavable container, showing our new design;
FIG. 2 is a top plan view thereof;
FIG. 3 is a front elevational view thereof;
FIG. 4 is a bottom plan view thereof; and,
FIG. 5 is an exploded perspective view thereof.
The broken line portions of the disclosure are for illustrative purposes only and form no part of the claimed design.
